DESIGN FOR A FIGURE TOY

Adelbert F. Filer, Memphis, Tenn., assignor of one-half to Martin J. Condon, Memphis, Tenn.

Application June 11, 1945, Serial No. 120,022

Term of patent 7 years

(Cl. D34—15)

To all whom it may concern:

Be it known that I, Adelbert F. Filer, a citizen of the United States of America, residing in Memphis, in the county of Shelby and State of Tennessee, have invented a new, original, and ornamental Design for a Figure Toy, of which the following is a specification, reference being had to the accompanying drawing, forming part thereof.

Fig. 1 is a front elevation.
Fig. 2 is a side elevation; and
Fig. 3 a rear elevation showing my new design for a figure toy.

I claim:
The ornamental design for a figure toy, substantially as shown.

ADELBERT F. FILER.
